AIR PROPELLER

Royal J. Reek, South Bend, Ind., assignor to Bendix Aviation Corporation, South Bend, Ind., a corporation of Delaware

Application April 11, 1946, Serial No. 661,426

4 Claims. (Cl. 170—160.11)

1

This invention relates to propellers, and more particularly to air propellers of the type in which the blades are arranged to be rotated about their axes in response to changing conditions of operation, such as number of revolutions of the propeller.

The present invention comprehends the provision of a variable pitch air propeller having a fine pitch setting in which it is held by the summation of the moments acting in a pitch decreasing direction, and a coarse pitch setting into which it is moved by the summation of moments acting in a pitch increasing direction.

It is an object of the invention to provide a variable pitch air propeller in which the centrifugal force of the propeller blades effect a change in blade pitch setting.

A further object of the invention lies in the provision of a variable pitch air propeller constructed and arranged so that its blades are normally in fine pitch position, but responsive to the centrifugal force of the blades above a predetermined value to cause the blades to shift to coarse pitch position with a snap action.

A still further object of the invention resides in the provision of a variable pitch air propeller movable from a normally fine pitch position to a coarse pitch position in response to the centrifugal force of the propeller blades acting through a ball nut assembly.

The above and other objects and features of the invention will be apparent from the following description of the apparatus taken in connection with the accompanying drawings which form a part of the specification, and in which:

Figure 1 is an elevational view of a propeller hub with portions broken away to show the internal mechanism;

Figure 2 is a transverse section of the hub taken substantially on the line 2—2 of Figure 1, with the propeller shown in coarse pitch;

Figure 3 is a transverse section of the hub taken substantially on the line 2—2 of Figure 1, with the propeller shown in fine pitch;

Figure 4 is a front elevational view partly in section of a propeller hub;

Figure 5 shows in diagrammatic view a modified form of cam used for a constant speed engine with automatic selection of governed speed;

Figure 6 is a diagram; and,

Figure 6a is a diagrammatic view of the two position cam and rollers of Figures 2 and 3.

Figure 7 is a diagram.

Referring now to Figure 1 of the drawings, the reference numeral 10 designates a propeller hub.

having a flange 12 which abuts a flange 14 carried by a propeller drive shaft 16 driven by an engine, not shown. The flanges 12 and 14 are drilled at 18 to receive bolts 20 to securely hold the flanges in abutting relationship. The ends of the hub 10 are formed with interiorly disposed helical grooves or races 22 which register with and are concentric to exteriorly disposed helical grooves or races 24 formed in members 25 which are drilled at 26 to receive lag screws 27 to secure the propeller blades 28 to said members. Balls 30 are received partly in each of the grooves 22 and 24 to provide a screw and nut assembly in which the hub may be considered the nut, and the member 25 the screw or ferrule. This arrangement provides a relatively frictionless assembly whereby the propeller blades 28 may be rotated about their axes. Tubes 31 provide return paths for the balls 30. It should be noted that the number of return tubes is optional, depending on the requirements of the assembly. The propeller blades are normally urged to fine pitch setting (see Figure 3) by a plunger 32 slidably located in bore 34 of the propeller shaft 16. A spring 36, having preselected characteristics, is disposed within the bore 34 so that its free end acts on the plunger to normally bias the same to the right. The plunger is provided with a stop element 38 located exteriorly thereof so as to engage an extension 40 of shaft 16 to limit the axial displacement of the plunger to thereby establish the maximum coarse pitch of the propeller blades (see Figure 2). The normal fine pitch setting of the blades is accomplished by constructing one end of the plunger with an extension 42 which abuts an adjustable plug 44 carried by the hub. This limits the axial displacement of the plunger 32 in a direction establishing the minimum fine pitch setting of the blades. The plug 44 provides means for adjusting the fine pitch setting of the blades within a predetermined pitch range. To facilitate assembly of the plunger 32 within the bore 34 a sleeve 48 is provided with a closed end portion 50 drilled at 52 to receive a bolt stud 54 which is screw-threaded into one end of the plunger. The end of the sleeve 48 opposite from the closed end is constructed with an outwardly turned flange 56 which engages one end of the spring 36, the opposite or free end of which abuts the plunger. The plunger 32, spring 36, sleeve 48 and bolt stud 54 comprise an assembly which is held together by the bolt stud 54 when removed from the bore 34. The members 25 into which the ends of the

propeller blades are fitted are equipped with integrally attached rollers 58. It should be noted that the rollers 58 are disposed outside of the axes of rotation of the blades to provide a lever arm for rotating the blades in a manner to be hereinafter described. The plunger 32 has a cam 60 integral therewith and on which the rollers 58 ride. The cam 60, of Figures 1 to 4, and 6a has two cam faces 62 and 64. The profile of the cam is determined by the requirements of the propeller blade pitch regulation. The instant cam is for a two-position propeller having fine and coarse pitch positions only with no intermediate pitch positions.

The arrangement of the mechanism is such that the centrifugal force of the propeller blades is resolved into a pitch increasing moment through the ball nut assembly. That is, the axial or centrifugal force of the propeller blades is converted into a torsional or twisting force which causes the blades to rotate about their axes in a pitch increasing direction. Also the aerodynamic forces acting on the propeller blades are in a pitch increasing direction. These latter forces are comparatively small and need not be considered in the present discussion.

Opposing these pitch increasing moments are pitch decreasing moments. The spring urged plunger and cam assembly provide a part of the pitch decreasing moment. In the instant case the blades are so arranged that the centrifugal twisting moment of the blades acts in a direction of pitch decreasing moment at all times to supplement the spring force.

In moving the propeller blades from a fine pitch position to a coarse pitch position it will be noted that the shift is against the spring loaded plunger 32 through the cam 60.

The spring 38 normally holds the propeller blades in a predetermined fine pitch position, as shown in Figure 3. In the case of the two-position cam the blades are always balanced in both positions. A predetermined definite force is necessary to cause the blades to be shifted from one position to the other. There is no range of blade pitch between fine and coarse pitch in the case of the two-position cam.

Figure 3 shows the propeller blade in a predetermined fine pitch position with the roller 58 riding on the cam surface 62. The layout of the cam surface 62 is such that the blades will remain in fine pitch until a predetermined propeller speed is attained, at which time the blades will be shifted to coarse pitch. That is, the rollers 58 will shift from cam surface 62 to cam surface 64. In coarse pitch the rollers 58 ride on the cam surface 64 which is constructed to provide an increased mechanical advantage. This increase in mechanical advantage, due to the difference in cam profiles allows a decrease in propeller speed within predetermined limits during the coarse pitch position and also makes available additional energy which is utilized to shift the propeller blades to coarse pitch with a snap action. Also, when in coarse pitch if the speed of the propeller blades falls below a predetermined value, the blades will be automatically shifted back to fine pitch position.

Action of the automatic two-position control can be best shown by reference to Figure 6. The ordinate of the graph represents degrees in propeller pitch displacement and the abscissa is laid off in inch-pounds. The pitch increasing moments being positive above the line $a-b$, and the pitch decreasing moments being represented by

a negative force below the line $a-b$. The pitch decreasing moments are shown as negative quantities since the summation of the pitch decreasing moments act in a direction to oppose the summation of the pitch increasing moments. Curves A and B represent the summation of the moments acting in a pitch decreasing direction at propeller speeds of 2000 and 2500 R. P. M. respectively. As indicated in the graph, with the blades in fine pitch position, it requires a pitch increasing force in excess of 1500 inch-pounds to rotate the propeller blades about their axes to thereby shift the blades to increase the blade pitch. At 2500 R. P. M. (see curve C) of the propeller blades the summation of the moments acting in a pitch increasing direction exceed the summation of the moments acting in a pitch decreasing direction to produce the aforementioned shifting of the blades to increase the blade pitch, that is, to shift the blades to coarse pitch. Curves D and E represent the fine and coarse pitch positions respectively of the propeller blades. The energy available for shifting the blades to coarse pitch is shown as a shaded area between the curves B and C. The energy available to shift the blades from fine to coarse pitch at 2500 R. P. M. with the rollers 58 on cam surface 62 is somewhat less than the energy available for completing the shift of the blades from fine to coarse pitch after the rollers 58 have been moved onto the cam surface 64 because of the increase in mechanical advantage. It will be noted, with reference to Figure 6, that the summation of the moments acting in a pitch decreasing direction diminish as the pitch tends to increase thereby increasing the unbalanced effect until the blades are urged into a coarse pitch position. After the shift of the blades to coarse pitch if the speed of the blades is reduced to 2,000 R. P. M. (see curve F), the summation of the pitch decreasing moments become greater than the summation of the pitch increasing moments to thereby cause the blades to resume fine pitch. The energy available for shifting the blades from coarse pitch to fine pitch position is shown by the shaded area between curves F and A.

Figure 5 shows an alternative form of cam 70 adapted to be used for maintaining a substantially constant speed of the engine with automatic selection of governed speed. The cam 70 comprises two cam faces 72 and 74 on which the rollers 58 ride. The action of the pitch increasing and pitch decreasing moments on the propeller blades where the cam 70 is used can be best shown in Figure 7. With reference to Figure 7, the ordinate represents degrees in propeller pitch displacement and the abscissa represents force in inch-pounds. The pitch increasing moments being considered positive above line $c-d$ and the pitch decreasing moments being considered negative below line $c-d$. Curve H represents the summation of the moments acting in a pitch decreasing direction. Curve K represents the summation of the moments acting in a pitch increasing direction at 2500 R. P. M. of the propeller. It should be noted that point P corresponds to the minimum fine pitch setting of the propeller blades. The blades are normally held in a predetermined fine pitch setting by the summation of the moments acting in a pitch decreasing direction. Curve T represents the summation of the moments acting in a pitch increasing direction at 2300 R. P. M. of the propeller. With this setting of the blades in fine pitch position the

rollers 58 will be in the position shown in Figure 5 at P' on cam face 72. When the propeller speed is increased, to Q the propeller pitch setting will have been increased and the rollers 58 will be in the position Q' on cam face 72. As soon as the propeller speed has reached 2500 R. P. M. indicated at S on curve K, the summation of the moments acting in a pitch increasing direction become sufficiently great to rotate the rollers 58 to S' on the cam surface 74 to thereby increase the mechanical advantage and to further shift the blades in a pitch increasing direction, which action tends to produce a reduction in the speed of the engine because of the increased load on the propeller. Of course, any further tendency to increase engine or propeller speed will cause a further shift of S' along cam surface 74 in a pitch increasing direction so as to put a greater load on the propeller blades. Obviously, with the cam arrangement of Figure 5 there are an infinite number of blade settings available for take-off and cruising. In the take-off pitch range, for example, there are an infinite number of blade settings available along cam surface 72 to maintain a speed of substantially 2500 R. P. M. When it is desired to cruise, the R. P. M. of the propeller is first caused to be increased above the 2500 R. P. M. so that the pitch increasing moments will become great enough to shift the rollers 58 onto the cam surface 74 and to increase the propeller blade pitch an amount which will load the blades to cause the R. P. M. to fall to substantially 2300 R. P. M., which has been selected as the cruising speed. In the cruising pitch range the same as in the take-off pitch range, there are an infinite number of blade pitch settings available to hold the propeller at substantially 2300 R. P. M.

Operation of the two-position device is as follows:

When the engine is idling, the summation of the moments acting in a pitch increasing direction is less than the summation of the moments acting in a pitch decreasing direction and the blades at this time are in fine pitch. During take-off, the increased power applied to the propeller increases the speed thereof to a value determined by the forward speed of the aircraft. After the aircraft has reached a speed of approximately 80% of its maximum speed, the propeller R. P. M. will have increased to 2500 and the summation of the pitch increasing moments will exceed the summation of the pitch decreasing moments to thereby shift the blades in a pitch increasing direction, at which time the rollers 58 ride on cam surface 64 of cam 60.

During cruising, the propeller is maintained in coarse pitch. However, should it be desired to climb or if the engine is throttled to land the aircraft, the propeller R. P. M. is reduced below 2,000 R. P. M. and the propeller blades are moved to fine pitch position. That is, at this time the summation of the moments acting in a pitch increasing direction become less than the summation of the moments acting in a pitch decreasing direction and the blades shift to fine pitch.

Although this invention has been described in connection with certain specific embodiments, the principles are susceptible of numerous other applications that will readily occur to persons skilled in the art. The invention is, therefore, to be limited only as indicated by the scope of the appended claims.

Having thus described the various features of

the invention, what I claim as new and desire to secure by Letters Patent is:

1. An air propeller comprising a revolvable hub with helical grooves formed in its ends, blades disposed in the ends of the hub revolvable therewith and rotatable about their axes; said blades having helical grooves at one end for mating with the grooves in the ends of the hub, balls having portions disposed partly in each of the mating grooves to provide a comparatively frictionless assembly for converting the centrifugal force of the revolving blades into a pitch increasing moment tending to rotate the blades about their axes to increase the pitch thereof, rollers carried by said one end of the blades and mounted eccentric to the axes thereof, means normally holding the blades in a predetermined fine pitch position including a plunger having a cam thereon engaging the rollers, and a spring for urging said cam against said rollers, whereby rotation of the blades from said predetermined fine pitch position in response to propeller speed beyond a preselected value moves the plunger against the force of the spring.
2. An air propeller comprising a revolvable hub with helical grooves formed in its ends, blades disposed in the ends of the hub revolvable therewith and rotatable about their axes, said blades having helical grooves at one end for mating with the grooves in the ends of the hub, balls having portions disposed partly in each of the mating grooves to provide a comparatively frictionless assembly for converting the centrifugal force of the revolving blades into a pitch increasing moment tending to rotate the blades about their axes to increase the pitch thereof, rollers carried by said one end of the blades and mounted eccentric to the axes thereof, means normally holding the blades in a predetermined fine pitch position including a plunger having a cam thereon engaging the rollers, means urging said cam against said rollers, whereby rotation of said blades from said predetermined fine pitch position in response to propeller speed beyond a preselected value moves the plunger against said last named means, and adjustable means carried by the hub for varying the predetermined fine pitch position of the blades.
3. An air propeller for use on an aircraft comprising a revolvable hub, blades disposed in the hub revolvable therewith and rotatable about their axes, means in the hub for converting the centrifugal force of the revolving blades into a pitch increasing moment tending to rotate the blades about their axes to increase the pitch of the blades, means normally tending to rotate the blades about their axes in a direction opposing the pitch increasing moment, said last named means comprising a cam carried by the hub and movable relative thereto, said cam being formed with surfaces which provide speed range settings for take-off and cruising, each range having an infinite number of predetermined blade pitch settings, means engaging the surfaces of said cam and carried by said blades, and means biasing said cam against said last named means.
4. An air propeller adapted to be driven by an engine and comprising a revolvable hub, blades having ends disposed in the hub revolvable therewith and rotatable about their axes, means in the hub for converting the centrifugal force of the revolving blades into a pitch increasing moment tending to rotate the blades about their axes to increase the pitch of the blades, means normally tending to rotate the blades about their

axes in a direction opposing the pitch increasing moment including a member carried on the end of each blade and located eccentric to the blades' axes, a cam movably mounted on the hub and formed with a pair of profiles, one of which is for take-off range and the other of which is for cruising range and against which profiles said members abut to thereby position the blades for a constant engine speed in any one of the ranges, with automatic selection of governed speed for both ranges, and means biasing said cam against said members.
